(57) **CLAIM**

We claim the ornamental design for a toner waste bin, as shown and described.

DESCRIPTION

FIG. 1 shows a perspective view of a toner waste bin according to my new design.

FIG. 2 shows a front elevation view thereof;

FIG. 3 shows a rear elevation view thereof;

FIG. 4 shows a top plan view thereof;

FIG. 5 shows a side elevation view thereof, the opposite side elevation view being a mirror image; and,

FIG. 6 shows a bottom plan view thereof.
